Application November 19, 1934, Serial No. 753,707

2 Claims. (Cl. 68—31)

My invention relates to laundry tubs formed of synthetic stone, and has among its objects and advantages the provision of an improved metal facing along the upper edge and partition of the tub.

In the accompanying drawing:

Fig. 1 is a perspective view of a tub embodying the invention;

Fig. 2 is a sectional view along the line 2—2 of Fig. 1;

Fig. 3 is a sectional view along the line 3—3 of Fig. 2;

Fig. 4 is a fragmentary detail view, partly in section, viewed from the position indicated by lines 4—4 of Fig. 3;

Fig. 5 is a perspective view of the corner connection between two pieces of metal facing; and

Fig. 6 is a plan view of a facing strip before it is formed.

In the embodiment selected to illustrate my invention, the tub 10 comprises end walls 12, side walls 14 and 16, and an integral partition 18. The tub is provided with a metal facing 20 along the upper edges of the end and side walls and a metal facing 22 along the upper edge of the partition 18. I provide one piece of facing for each of the walls, which pieces are shaped to assemble in interfitting relation to provide effective metallic covering for the corner portions of the tub, as indicated at 24.

Referring to Fig. 2, the facing 20 comprises a single strip of sheet metal bent to provide a flat top surface 26 and a wall lining surface 28 separated from the surface 26 by the curved corner portion 30. The other edge of the surface 26 is bent at 32 and again at 34 to offset a portion of the strip with respect to the surface 26, which offset portion is bent to provide a curved part 36 and an inwardly projecting flange 38. Similarly the wall lining 28 is bent at 40 to provide an inwardly projecting flange 42. Both flanges 38 and 42 are imbedded in the concrete comprising the wall 14, the material of which completely fills the metallic facing.

The specific configuration of the facing in cross-section provides a tub edge devoid of sharp corners in addition to enhancing the ornamental appearance of the finished product. At the same time the curved parts 30 and 36, together with the offset part between the lines 32 and 34, provide a reinforced facing capable of withstanding rough usage. Because of this construction the individual facing pieces will retain their original straight alignment so that the finished edges of the tub will always be true in addition to eliminating the difficulty of accurate placement within

the mold so that straight tub edges may be formed.

I have discovered that a metallic facing having a surface 26 extending the full width of the upper edge of the tub tends to buckle after its association with the wall of the tub so that the facing will have a wavy appearance. My reinforced construction, together with the narrow surface 26, prevents buckling of the metal.

My corner connection between the individual pieces of the facing 20 is designed to provide a blunt or curved corner 44, thereby eliminating the sharp corner characteristic of commercial tubs.

Referring to Fig. 5, each piece of the metallic facing 20 has an end 46 terminating in a straight line at right angles to the longitudinal axis of the piece, and its opposite end bent to provide a lip 48 arranged at right angles to the piece proper.

In Fig. 6 I illustrate the lip 48 as being formed integrally with the facing proper, which lip is bent generally along the line 50 to provide a curved vertical corner 52 and shaped in the area indicated generally at 54 to provide the curved corner 44. In cutting the blank, as indicated in Fig. 6, the corners 44 and 52 may easily be formed by a die to provide a gentle curvature of smooth configuration.

The lip 48 is arranged in interfitting relation with the end 46 of its associated facing piece. I bend the lip 48 at 56 to provide a flange having a curvature conforming to the curved part 30. Before the two parts are assembled, the flange 42 is bent, as indicated at Fig. 5, to provide a trough 58 for the reception of a portion of the lip 48. While the lip 48 lies inside the lining surface 28, the remaining portion of that piece of facing 20 lies over a portion of the straight end of the other piece, as indicated by the overlapping illustration of Fig. 4.

Referring to Fig. 6, the V-shaped end portion 60 provides an end formation when the blank is bent into the finished article which closely embraces the curved part 36 and the flange 38. This arrangement provides an effective connection in which the tendency for either part to shift with respect to the other by rotary movement about its longitudinal axis is entirely eliminated.

I have also found that the reinforced construction prevents portions of the overlapping parts of the interfitting facing pieces from bending easily so that very little difficulty is experienced in assembling the pieces within the form preparatory to pouring the concrete.

In Figs. 3 and 4 I illustrate the shape of the metallic facing 22 for the partition 18. This piece

is bent to provide a flat surface 62 and two curved and flanged edge parts 64 conforming in configuration to the cross-sectional shape of one side of the facing pieces 20.

- 5 In Fig. 4 the facing 20 associated with the wall 16 is cut out at 66 to receive the facing 22. The shape of the cut-out is illustrated in Fig. 5. In Fig. 4 I illustrate the ends of the facing 22 as being straight and in right-angular relation with 10 the facing proper with a portion of the surface 62 as lying underneath the surface 26 of the associated facing 20.

Without further elaboration, the foregoing will so fully explain my invention that others may, 15 by applying current knowledge, readily adapt the same for use under various conditions of service.

I claim:

1. In an upright tub wall having an angle 20 therein, metallic facings along the top surface of the wall and having flanges extending downwardly over portions of the outer faces of the wall, the ends of said metallic facings having overlapping relation at the angle of the wall, one of 25 said metallic facings being provided with a con-

vex area extending around the outer sides and top of the wall at said angle, said flanges including inturned portions anchored in the material of the wall, one of said flanges being bent back upon itself to provide a trough for the reception 5

2. In an upright tub wall having an angle therein, first and second metallic facings extending along the top surface of the wall, each of said facings including flanges extending downwardly 10 over portions of the outer faces of the wall, the first of said metallic facings having a straight end arranged at right angles to the longitudinal axis of its facing, the second of said metallic facings having a flange lip forming a part of its outer 15 flange and arranged at right angles to the longitudinal axis of said second facing and extending under the outer flange of said first facing, the outer flange of said first facing being bent back upon itself to provide a trough for the reception of 20 said lip, a portion of said lip and its metallic facing being provided with a convex area extending around the outer sides and top of the wall at said angle.
